UNITED STATES PATENT OFFICE.

THADDEUS W. KELTON, OF VAN BUREN, ARKANSAS.

DESIGN FOR A DENTAL LAVATORY.

51,016.

Specification for Design. Patented July 10, 1917.

Application filed April 14, 1917. Serial No. 162,194. Term of patent 14 years.

To all whom it may concern:

Be it known that I, THADDEUS W. KELTON, a citizen of the United States, residing at Van Buren, in the county of Crawford and State of Arkansas, have invented a new, original, and ornamental Design for a Dental Lavatory, of which the following is a specification, reference being had to the accompanying drawing, forming part thereof.

The figure is a perspective view of a dental lavatory, showing my new design.

I claim:—

The ornamental design for a dental lavatory, as shown.

THADDEUS W. KELTON.

Witnesses:

D. C. BUEL,

C. M. BLEDSOE.
